UNITED STATES PATENT OFFICE.

FREDRIC D. OGDEN, DECEASED, LATE OF BAYONNE, NEW JERSEY, BY JOHN EDWARD OGDEN, ADMINISTRATOR, OF BROOKLYN, NEW YORK, ASSIGNOR TO THE PATENT APPLIANCE COMPANY, OF NEW YORK, N. Y., A CORPORATION OF NEW YORK.

DOOR AND MEANS FOR OPERATING THE SAME.

1,090,491.

Specification of Letters Patent. Patented Mar. 17, 1914.

Application filed February 23, 1912. Serial No. 679,751.

To all whom it may concern:

Be it known that FREDRIC D. OGDEN, deceased, formerly a citizen of the United States, and a resident of Bayonne, county 5 of Hudson, and State of New Jersey, did, prior to his decease, invent certain new and useful Improvements in Doors and Means for Operating the Same, of which the following is a specification, reference being had 10 to the accompanying drawings, forming a part thereof.

This invention relates to an improvement in doors and their operating mechanism, and especially to such doors as are used for 15 closing large openings or doorways in pier sheds, factories, warehouses, and the like.

The object of the invention is to provide a simple door and its operating mechanism, applicable more particularly to what are 20 known as single-section doors, although obviously not limited to doors of this particular type, which is inexpensive, and easily manipulated and which has advantages over such devices as have been in use heretofore.

I will describe my invention in the following specification and point out the novel features thereof in appended claims.

Referring to the drawings: Figure 1 is an 30 inside front elevation of a door embodying the invention. Fig. 2 is a transverse vertical section of the same. Fig. 3 is a plan view of the door and its mounting. Fig. 4 is a fragmentary side elevation showing a portion of the hoisting mechanism. Fig. 5 is a sectional plan view of portions of the door and the door frame above the rollers 35 27-28 and Fig. 6 is a similar section of like parts below the rollers.

As illustrated in the drawing, the door 10 40 is composed of a single section of any approved construction, and arranged to close the space between the side walls 12 of a doorway. The outer face of the door adjacent its lower edge is provided with an 45 angle iron 14 having its lower flange projecting from the face of the door. This flange rests upon the floor when the door is closed, and acts as a water-shed when the door is raised to its dotted line position 50 shown in Fig. 2.

A pair of Z-bars 16 are mounted on the side walls on each side of the door opening. They extend from the floor up over the

lower part of the opening and their inner flanges project slightly inside of the door 55 opening and act as stops to limit the inward movement of the lower end of the door. A pair of locking bolts 18 may also be provided to secure the door in closed position. The lower part of the door is preferably formed 60 without panels on the outside so as to provide a smooth surface which will readily shed water when the door is open.

The door is raised by two hoisting chains 20 and 21, connected at one end to swiveled 65 arms 22-23 respectively, at least one of which is provided with a threaded eye-bolt or other device for adjusting the length of the chain. These arms are pivotally mounted on studs 24 projecting from blocks 25-26 70 respectively, which are mounted on the inner face of the door, intermediate the top and bottom thereof and adjacent its edges. Rollers 27-28 are pivotally mounted on the studs 24 and as the door is raised roll on the 75 inner face of the wall of the door opening on which tracks 19 are provided for them. The pivots 24 also act as rolling pivotal centers for the door during its raising or lowering movement. The chain 20 passes from 80 the arm 22 over an idler sheave 30, which is pivotally mounted in a bracket 32, supported near the top of the doorway; over one side of a double-grooved pocket wheel 34, carried by a shaft 35, mounted in a 85 housing 30; and thence down to the counter-weight 38 to which it is attached. The chain 21 passes over the other half of the double-grooved pocket wheel 34, and is also attached to the counter-weight 38. 40 is a 90 hand chain which passes over a chain sprocket 42 on a shaft 43, on which is a pinion 44, which meshes with a gear 46 on the shaft 35, and thereby drives the double grooved pocket wheel 34. A pair of chains 95 50-51 may be attached at one end to the upper edge of the door, and at their other ends to the ceiling 52. If desired these chains may be attached to the wall above the door opening. The chains 50-51 support 100 the upper edge of the door after it is raised and prevent its inner edge being pulled downward if any undue weight is placed upon it.

A pair of links 55-56 are pivotally 105 mounted at their upper ends in bearings

57—58, respectively, secured to the wall adjacent the upper corners of the doorway. The lower ends of these links are pivotally mounted in brackets 59—60, respectively, secured to opposite edges of the inner face of the door. By pulling the chain 40 the double pocket sheave 34 may be rotated to raise or lower the door. By reference to Figs. 2 and 4, it will be seen that the upward pull on the door exerted by the chains 20—21, on the pivots 24 causes the door to be raised and at the same time the links 55—56 force the upper part of the door inward as the pivotal supports for the lower ends of the links in brackets 59—60 are inside of lines drawn between pivots 57 or 58 and the pivots 24. As the door continues to move upward the rollers 27—28 roll up on the tracks 19 on the inner face of the wall 12 and the upper end of the door continues to be forced inward by the links 55—56 and finally assumes some such position as that in which it is shown in dotted lines in Fig. 2.

The upper part of the door, or that part which is above the pivots 24 is made somewhat wider than the doorway, while the part below the pivots is narrower so that it may swing freely through the doorway. This narrower part of the door abuts against the Z-bars when the door is closed.

From the foregoing description it may be seen that the door when closed may form a wind and water-proof closure, which may be readily raised into a position to leave the entire doorway clear. In its raised position part of the door projects outwardly from the structure thus forming a canopy over the doorway. It may be slightly inclined when in its raised position so that it will allow water to run off freely, and the angle iron is provided so that the water will drip from its corners only. It is usual to place the pivots 24 slightly below the center of the door, and when so placed about one half of the door will be inside and one half outside of the building when the door is raised. This however is not essential as the pivots may be placed considerably above or below the center as long as they are in axial alignment. Thus the proportion of the door which projects outside of the building when the door is raised, may be varied as desired. The angle of inclination of the door in raised position may also be varied to suit requirements by proportioning the length and the positions of the supports of the links 55—56. The advantages of this construction when used for the doors of shipping rooms, freight houses, or other similar openings, are obvious.

I have described and claimed a structure with the upper part of the door wider and the lower part narrower than the doorway, but it is obviously within the scope of this invention to invert this arrangement and to

so change the mechanism that the upper part of the door may be swung outward to form a canopy.

What I claim is:

1. A door, hoisting means therefor, pivotal connections between the hoisting means and the door at opposite edges of the door and intermediate its length, the part of the door above the pivotal connections being wider than the doorway and the part of the door below said connections being narrower than the doorway, and edge strips for engaging the narrow portion of the door, whereby the door can only be swung in one direction on its pivots as it is raised by said hoisting means. 70

2. The combination with a doorway having offset side strips extending from the base upward approximately half way to the top, a door which is vertical when closed, the upper part of the door being wider and overlapping the sides of the doorway and the lower part being narrower and adapted to close against said offset side strips, pivots projecting outward from the respective sides of the door at corresponding intermediate points therein, hoisting means pivotally connected to said pivots and a link connected with the door above said pivots and to a relatively stationary part over the doorway, and means for actuating the hoist whereby the lower part of the door swings through the doorway and the door is raised to a position slightly inclined from the horizontal. 85

3. The combination with a vertically movable door, of means connected to said door at opposite edges thereof intermediate its length for hoisting the door, links pivotally connected to the door at opposite edges thereof above and inside of the point of attachment of the hoisting means for forcing the upper portion of the door inward as the door is raised, rollers on said door arranged to roll along the wall adjacent the doorway and providing a pivotal support for the door, the upper part of the door above the pivotal connections being wider than the doorway and the part of the door below said connections being narrower than the doorway, and offset edge strips of Z-section for engaging the narrow portion of the door whereby the door can only be swung in one direction on its pivots. 100

4. The combination with a doorway having offset side-strips extending from the base upward approximately half way to the top, a door which is vertical when closed, the upper part of the door being wider and overlapping the sides of the doorway and the lower part being narrower and adapted to close against said offset side strips, a base strip on the lower edge of the door, pivots projecting outward from the respective sides of the door at corresponding intermediate points therein, guide rollers for the door 110

- tatively mounted upon said pivots, hoisting chains each having one of its ends pivotally connected to one of said pivots and a link connected with the door above said pivots 5 and to a relatively stationary part over the doorway, a counterweight for the door, said chains being connected with the counterweight, a pocket sheave for said chains, and means for imparting rotation to said sheave.
- 10 whereby the lower part of the door swings through the doorway when the door is raised by said hoist to a position slightly inclined from the horizontal, the lower portion of the door constituting a shed over the doorway.
- 15 and the said base strip constituting a water deflector therefor.
5. The combination with a door which is vertical when closed, of a pair of chains arranged to hoist said door, rollers at the edges 20 of the door arranged to engage the inner face of the wall adjacent the doorway, a pair of links each connected at one end to the door and at its other end to the wall adjacent the doorway, arranged to force in and to 25 guide the upper end of the door whereby the latter is swung inwardly as the door is raised with its lower portion projecting outward over the doorway; and a water shedding strip on the lower edge of the door.
- 30 6. The combination with a doorway, a door which is vertical when closed, the upper part of said door being wider and the lower part of the door narrower than the space between the walls of said doorway, pivots pro- 35 jecting outward from each side of the door, said pivots being in axial alinement with each other, guide rollers for the door, rotatably mounted upon said pivots, hoisting chains pivotally connected with said pivots, and a link connected with the door above 40 said pivots and to a part stationary relative to the doorway, arranged to force the upper part of the door inward as the door is raised.
7. The combination with a doorway, a door which is vertical when closed, the upper 45 part of said door being wider and the lower part of the door narrower than the space between the walls of said doorway, pivots projecting outward from the respective sides of the door, said pivots being in axial alinement with each other, guide rollers for the door, rotatably mounted upon said pivots, hoisting chains each having one of its ends 50 pivotally connected with said pivots, and a link connected with the door above said pivots and to a part stationary relative to the doorway, arranged to force the upper part of the door inward as the door is raised; a counterweight for the door, said chains being connected with the counterweight, a 55 pocket sheave for said chains, and means for imparting rotation to said sheave.

In testimony whereof, I have signed this specification in the presence of two subscribing witnesses.
